UNITED STATES PATENT OFFICE.

WILLIAM E. TOURTELLOTTE, OF SAN MATEO, CALIFORNIA.

MOLD FOR CONCRETE WALL, COLUMN AND GIRDER CONSTRUCTION.

1,323,557.

Specification of Letters Patent.

Patented Dec. 2, 1919.

Application filed July 17, 1917. Serial No. 181,185.

To all whom it may concern:

Be it known that I, WILLIAM E. TOURTELLOTTE, a citizen of the United States, residing at San Mateo, in the county of San Mateo and State of California, have invented certain new and useful Improvements in Molds for Concrete Wall, Column and Girder Construction, of which the following is a specification.

This invention relates to molds or forms for the construction of concrete walls, columns, girders and the like, and has for its main object to simplify the construction of the parts of the molds so that they may be readily assembled and taken apart and reassembled.

In the accompanying drawings, Figure 1 is a perspective view of a portion of a mold embodying my invention; Fig. 2 is a perspective view of the tie-clip shown in Fig. 1; Fig. 3 is a vertical section thereof showing the manner of tying the sides of the mold together; Fig. 4 is a horizontal sectional view showing a corner section of my mold; Fig. 5 is a vertical section of a mold showing the manner of constructing the tie-plates to hold a veneer facing of concrete; Figs. 6 and 7 are perspective views of semi-tie-plates, of the type shown in Fig. 5; Figs. 8 and 9 are a horizontal section and side elevation of a mold in position to pour a section of a wall and showing the manner of turning angles; Fig. 10 is a detail perspective view showing the manner of making a bend in a wall; Figs. 11 and 12 are perspective views of the angle clips which hold the perpendicular brace members at the corners of a wall; Figs. 13 and 14 are top plan views of integral tie-clips employed respectively at the corners and intermediate points in the mold forms; Fig. 15 is a fragmentary perspective, partly in section, showing the manner of tying a mold constructed of boards; Figs. 16 and 17 are diagrammatic views showing the manner of securing the horizontal brace members in the tie-clips; Fig. 18 is a horizontal sectional view showing the manner of constructing a corner section of the mold when employing wooden mold forms; Figs. 19, 20 and 21 are detail views of fastening plates for splicing the meeting ends of vertical brace members; Fig. 22 is a perspective view of a modified form of tie-clip; and

Fig. 23 is a perspective view of another form of tie-clip and showing the manner of arranging it on the wooden form boards.

One of the main purposes of my invention is to provide a mold in which the perpendicular brace and reinforcing members are securely tied together by metal tie-clips which also form ledges or supports for the horizontal brace members that extend between the perpendicular braces and determine the spaces therebetween, locking the parts into an interconnected system.

The perpendicular braces 2, and the horizontal braces 4, may be in the form of channel irons. I also preferably employ, for light constructions, perpendicular reinforcing channel bars 5, which pass up through the mold space and become a part of the wall structure and to which may be attached light reinforcing members, such as wire lath or wire fencing.

As previously stated, an important feature of my invention is the manner in which the system of brace members are secured together by means of tie-plates or clips. While I may employ integral clips such as shown in Fig. 14, I prefer to make the tie-clips in halves as shown in Fig. 2, the two sections 7, being placed upon opposite sides to embrace a pair of perpendicular braces 2 and an intermediate reinforcing member 5 as shown in Fig. 1. The clip sections are then preferably welded to each other at the meeting edges and also to the perpendicular members, the welds being conveniently made by the electric, oxyacetylene or other process. In this manner the bracing is not only made very strong and rigid, but the weight of the forms is also distributed along the upright members. After the concrete walls have set and hardened, the sheet metal tie-clips can be readily cut by shearing or by the oxyacetylene torch so that the brace members can be removed. The horizontal brace members 4 extend between the perpendicular braces 2, determining the spaces therebetween and uniting the braces into a connected or interlocked system. These horizontal braces are two or more feet apart and are preferably notched at the ends where they rest upon the tie-clips, as shown in Figs. 9 and 16, so that they will drop down and cover the joint between the adjacent horizontal rows of form boards 8, and se-

surely brace the margins against outward pressure. The vertical joints between abutting form boards may be made tight by grooving the meeting edges and inserting 5 slip-tongues 10, which may also extend at each end into grooves or recesses in the boards above and below, the intermediate boards being also tied together by metal tongues 12, inserted at suitable distances 10 apart in grooves or recesses. It is evident that boards of any convenient width may be used and of any different lengths, so that there is practically no waste whatever. The form boards may be cleaned and used repeatedly, being preferably treated in a manner 15 to render them impervious to moisture.

The form boards rest upon the tie-clip 7, where they pass the perpendicular braces and are prevented from falling inward until 20 the cement is poured by the lugs 7^a on the clips which project over the edges of the boards.

When it is desired to face the wall with a veneer finish, such as made from Portland 25 cement, or cements having a magnesite base or veneers made from clay products, I extend the outer ends of the tie-clips and bend them into oppositely turned lugs 7^b as shown in Figs. 6 and 7, which are embedded in the 30 facing 6 and tie it to the main body of the wall by means of the tie-clips, as illustrated in Fig. 5. The lugs 7^b may be reinforced by means of a square plate welded thereto, as shown in Fig. 7.

35 In Fig. 15 I have shown another form of tie-clip or plate for use with wood mold forms in which the end rectangular openings are elongated sufficient to permit the forming of the metal at the inner ends to burs 40 or tongues 7^b, bent in opposite directions so that they will cut into the boards to act as anchors to prevent any slipping or movement of the boards. Instead of welding the two sections of the tie-clips together, they 45 may be joined by passing tie wires 15 through holes punched in the ends of the plates and twisting the ends of the wires together. In Fig. 23 I have shown a tie-clip 7' which is stamped from an integral plate 50 or sheet of metal and is provided with flanges 7^c which are bent in opposite directions between the form boards and serve to stiffen the plates against deflection due to 55 the falling of concrete thereon when the wall is in process of pouring.

In Fig. 18 I have shown the manner of constructing a corner of the wall with wood forms. The tie-plate is cut, either as an integral plate or in halves 9, to fit between the 60 inner and outer form boards with an external wedge-shaped angle at the outer side and with an internal or reentrant angle at the inner side. An angle piece 11, shown in detail in Fig. 12, is then placed about the 65 double channel vertical brace members 2,

the inner ends being welded, as indicated at 2^a to the edges of the plates 9. Each arm of the angle brace 11 is provided with tongues or burs 7^a to cut into the form boards to more securely anchor them against 70 movement. At the outer side of the corner I provide rectangular wing plates 11^c which are provided with apertures to receive the vertical channel bars 2, with room also for the depending hook portions or tongues of 75 the horizontal braces 4, these wings being welded to the plates 9 at their inner ends as indicated at 11^b. I also cut other apertures in these plates and form a portion of the metal into tongues or burs 7^a which cut into 80 the mold boards to serve as anchors therefor. One of the form boards 8' may extend outwardly beyond the other at the corner, as indicated, therefore avoiding the necessity of cutting the board. The corner is securely 85 braced by means of horizontal braces 4 extending in each direction from the corner, the opposite ends being hooked into the recesses of the next adjacent tie-plates, which may be like those shown in Fig. 2 or in Fig. 90 14. When using wood form boards, as shown in Fig. 15 it may not be necessary to use horizontal braces except those extending each way from the corner. Light reinforcing material 16, such as wire netting, sheet 95 metal, lathing, etc. may be secured to the intermediate vertical bars 5 to serve as reinforcements extending through the interior of the cement wall.

Instead of using boards for the mold forms 100 as in Fig. 1, 3, 15 and 18, I may employ sheets of metal of convenient widths to extend between the horizontal braces, the joints between the sheets being covered by the braces in the manner previously described. I have 105 illustrated the manner of using sheet metal plates 8^a in Figs. 4, 8, 9 and 10. To form a corner, one sheet may have an end margin bent at the required angle, the meeting sheet being fitted into the angle thus formed to 110 close the corner joint, as I have shown in Fig. 4. Within the inner corner I make the perpendicular brace of double strength by placing two channel irons together, while at the outer side of the corner, I employ two 115 separated channel irons. While I may use integrally formed tie-clips with apertures to fit over the brace members and the intermediate reinforcing member as illustrated in Fig. 13, I prefer to form the corner tie-clips 120 in several parts as illustrated in Fig. 4. The inside parts 9 embrace the reinforcing channel bar 5 and bear at each end against the diagonally opposite brace members 2. The parts 9 are secured to the inner vertical 125 braces 2 by means of an angle piece 11, shown in detail in Fig. 12, which engages the braces on two sides and overlaps the parts 9, to which the ends are welded. The small projection in the angle of the angle 130

piece 11 holds it away from the sides of the braces 2, to provide slots to receive the hooked ends of the horizontal braces 4. The outer corner braces 2 are surrounded by the 5 U-shaped members 11^a, shown in detail in Fig. 11, and having their ends overlapped upon the inner clip members 9, to which they may then be welded. When the parts are thus welded together and to the upright 10 braces, a very rigid corner is formed. The parts 9 may be provided with lugs 7^a to bear against the inside faces of the form sheets 8^a and hold them in position until the cement is poured. In Figs. 8, 9 and 10, I have 15 illustrated the manner in which my forms may be accommodated to walls which turn at various angles. The construction will be clearly understood from the previous description without further detailed explanation. The sheets may be of varying lengths, 20 the ends being overlapped and braced by vertical channel bars connected together by tie-clips in the manner previously described.

I have indicated in Fig. 16 the manner 25 in which the horizontal brace members 4 are secured in the tie-clips or plates which surround the vertical brace members, so that the entire structure is completely surrounded by a continuous interconnected system 30 of horizontal braces. As previously explained, the apertures in the ends of the tie-plates are cut large enough to provide a slot upon each side of the vertical channel bars 2, to receive the hooked ends of the horizontal bars. The opposite ends of the bars 35 4 are notched to form hooked ends, the notch 4^a at one end being cut to form a locking or bayonet slot, while the opposite end is slotted at 4^b to form a somewhat plane 40 curved hook. The end 4^b is first inserted into the slot in one of the tie-clips, the bar being held in a downwardly inclined position, as indicated in Fig. 16 until the hook engages the slot, and the bar is then raised 45 in the direction of the arrow into a horizontal position and the end 4^a is dropped into the slot of the next adjacent tie-plate. When the end 4^b of the next bar is inserted in the slot upon the opposite side of the clip in 50 which the last end 4^a of the preceding bar was inserted, the clip will be drawn over toward the left as the horizontal brace is raised into horizontal position thereby locking the opposite side of the clip in the notch 55 of the bayonet notch 4^a, as indicated in Fig. 16. This process is repeated until the last horizontal brace is laid in place. In order to insert the closing end of the last horizontal brace in the clip at the last 60 upright, which has already received the first end of the first horizontal brace, it is necessary to cut the slots in this clip somewhat wider than the slots in the others in order that the end of 4^a of the last brace may be 65 slipped into position. There will, therefore,

remain a small space between the end of this last horizontal brace and the side of the adjacent upright channel bar. This clearance space may be closed by means of a metal key driven thereinto and the whole 70 tier will thus be locked by an interconnected chain of horizontal brace members. I have shown in Fig. 17 another method of securing the end of the last horizontal brace in the series. The upright at this connecting 75 clip may be cut with its ends tapering into wedges as indicated in Fig. 17. After the last horizontal member has been slipped into position, the upper portion of the upright may be driven downwardly to thereby wedge 80 the boards tightly together. In each case, therefore, the horizontal boards form an interconnected continuous chain surrounding the entire mold form of the wall.

It is frequently desirable to splice or connect the ends of upright or vertical brace members so that they will form, in effect, a continuous brace. In Figs. 19, 20 and 21 I have shown a very efficient slip joint for thus uniting the meeting ends of vertical 85 brace members. Each of the meeting ends of the vertical channel bars may be provided with a bayonet notch 20, the slots being oppositely arranged and with a small semicircular notch in the ends. A rectangular 90 filler bar 23, adapted to fit into the channel of the bars is provided with headed screws 24 threaded therein and arranged so that the notches 21 will fit around the central screw and the narrow extensions of the slots 20 100 will engage the other screws when the boards are in position as indicated in Fig. 19. It will be apparent that the vertical channel bars may be united by slightly separating their ends until the heads of the screws have 105 been inserted through the larger portions of the slots 20 and then lowering the upper brace until the necks of the screws have entered the narrower portions of the slots 20, the notches 21 fitting around the neck 110 of the central screw.

The several advantages to be derived from the use of my mold forms and my method of assembling the parts will be especially appreciated by constructing engineers and 115 those familiar with the present methods of pouring concrete walls. I have greatly reduced the number of parts required for setting up the molds and have taken advantage of the recent advance in rapid welding 120 methods which enables me to use standard rolled iron shapes, such as channel bars, together with a few shapes of clips which may be stamped out of sheet metal in certain standard sizes. When boards are employed 125 they can be any convenient width and of random lengths different widths being used to make up the desired height. Likewise when sheet metal is used for the sides of the forms, they may be of any suitable width 130

and in varying lengths, and in either case the boards and metal sheets can be used again and again.

My improved tie-clip enables me to readily assemble the vertical and horizontal channel iron braces and to unite them into an interlocked system which affords ample strength and rigidity. It will be understood that I can employ other rolled shapes such as I-beams, if desired or more convenient, and these are included in the term "channel beams".

I have described in detail the particular construction shown in the accompanying drawings for the purpose of illustrating an embodiment of my invention, but I wish it understood that various changes and modifications can be made therein to suit varying conditions within the scope of my claims and without departing from the spirit of my invention.

I claim:

1. A mold for concrete walls and the like, comprising side members upon opposite sides of the wall space, oppositely arranged upright metal beams upon the outside of said side members, horizontal beams extending between and spacing said upright members apart, and tie-clips connecting said upright beams and supporting the ends of said horizontal beams to form an interconnected bracing system.

2. A mold for concrete walls and the like, comprising side members upon opposite sides of the wall space, oppositely arranged upright metal beams upon the outside of said side members, horizontal beams spacing said upright members apart, and tie-clips connecting said upright beams and supporting the ends of said horizontal beams to form an interconnected bracing system, said horizontal beams covering the joint between the adjacent side members, and said tie-clips having lugs engaging the side members to prevent inward movement before the concrete is poured.

3. A mold for concrete walls and the like, comprising side members upon opposite sides of the wall space, oppositely arranged upright metal beams upon the outside of said side members, horizontal beams extending between and spacing said upright members apart, and tie-clips connecting said upright beams and supporting the ends of said horizontal beams to form an interconnected

bracing system, and each being provided with an aperture to locate it with reference to a central reinforcing upright.

4. A mold structure for concrete walls and the like, comprising a system of brace members consisting of oppositely arranged upright channel beams, tie-clips surrounding and connecting said beams, and channel beams extending horizontally between adjacent upright beams upon the same side of the mold and having their ends resting upon said tie-clips.

5. A mold structure for concrete walls and the like, comprising a system of brace members consisting of oppositely arranged upright channel beams, tie-clips surrounding and connecting said upright and reinforcing beams, and channel beams extending horizontally between adjacent upright beams upon the same side of the mold and spacing them apart, and having their ends resting upon said tie-clips, each of said tie-clips being provided with an aperture to locate it with reference to a central reinforcing upright.

6. A mold for concrete walls and the like, comprising side members upon opposite sides of the wall space, oppositely arranged upright metal beams upon the outside of said side members, horizontal beams spacing said upright members apart, and tie-clips provided with apertures through which said upright beams extend, said horizontal beams being provided with hooked ends which extend into said apertures to link the horizontal members into a connected series.

7. In a mold structure for concrete walls mold panels, a system of brace members consisting of channel beams, and means for connecting the meeting ends of said members, comprising key-hole slots oppositely disposed in the ends of the beams and a filler bar provided with lugs or screws having heads adapted to pass through the larger ends of said slots and to extend over the narrow ends of the slots when the ends of the beams abut.

In testimony whereof I affix my signature in presence of two witnesses.

WILLIAM E. TOURTELOTTE.

Witnesses:

JOSEPH B. GORDON,
HAZEL ROTH.
